F. W. HELWIG.
FOLDABLE TRESTLE.
APPLICATION FILED OCT. 31, 1916.

1,243,520.

Patented Oct. 16, 1917.

UNITED STATES PATENT OFFICE.

FRANK W. HELWIG, OF MILLERSBURG, PENNSYLVANIA.

FOLDABLE TRESTLE.

1,243,520.

Specification of Letters Patent. Patented Oct. 16, 1917.

Application filed October 31, 1916. Serial No. 128,714.

To all whom it may concern:

Be it known that I, FRANK W. HELWIG, a citizen of the United States, residing at Millersburg, in the county of Dauphin and State of Pennsylvania, have invented certain new and useful Improvements in Foldable Trestles; and I do hereby declare the following to be a full, clear, and exact description of the invention, such as will enable others skilled in the art to which it applies to make and use the same.

The invention relates to improvements in foldable trestles.

The object of the present invention is to improve the construction of folding trestles and to provide a simple, practical and efficient folding trestle of strong, durable and comparatively inexpensive construction designed for the use of carpenters and various artisans and capable of being readily folded and compactly arranged when not in use and adapted to be easily and quickly set up for use.

A further object of the invention is to provide a folding trestle of this character equipped with a foldable rest adapted to receive and support the horizontal top connecting bar or member of the trestle and capable of being compactly arranged between the legs or standards of the trestle when the latter is folded.

With these and other objects in view, the invention consists in the construction and novel combination of parts hereinafter fully described, illustrated in the accompanying drawing, and pointed out in the claims hereunto appended; it being understood that various changes in the form, proportion, size and minor details of construction, within the scope of the claims, may be resorted to without departing from the spirit or sacrificing any of the advantages of the invention.

In the drawing

Figure 1 is a side elevation partly in section of a folding trestle constructed in accordance with this invention,

Fig. 2 is an end elevation of the same,

Fig. 3 is an enlarged detail elevation of the upper portion of one end of the trestle,

Fig. 4 is a detail longitudinal sectional view of the upper portion of one end of the trestle showing one of the supports or rests,

Fig. 5 is a detail vertical sectional view on the line 5—5 of Fig. 4.

Like numerals of reference designate corresponding parts in the several figures of the drawing.

In the accompanying drawing in which is illustrated the preferred embodiment of the invention, the foldable trestle comprises in its construction inclined legs or standards 1 constructed of angle metal and provided with lower extensible sections 2 adapted to vary the height of the trestle and secured to the legs or standards 1 by bolts 3. The legs or standards 1 and the sections 2 are provided with registering perforations 4 and 5 and the bolts 3 are equipped with tail nuts 6 for clamping the sections of the legs or standards in their adjustment. Any other suitable means may of course be employed for adjustably connecting the sections of the legs or standards. By varying the length of the legs or standards the trestle may be arranged for various uses such as plastering rooms of different sizes and the trestle is adapted to take the place of an ordinary scaffold. The legs are connected adjacent to their upper ends by a horizontal link or bar 7 pivoted at its ends at 8 to the legs 1 and adapted to permit the legs to be arranged substantially parallel to permit the introduction of a timber 9 between their upper ends and the said legs are also adapted to be swung outwardly to an inclined position as illustrated in Fig. 2 of the drawing for causing their upper ends to firmly clamp and grip the timber 9. The legs also are inclined inwardly in a direction longitudinally of the foldable trestle as clearly illustrated in Fig. 1 of the drawing. In practice, the trestle when constructed for ordinary use will be of a size to clamp and securely grip a timber two inches thick and a two by four, two by six or two by eight or any other size timber may be used to enable a trestle of the desired length to be erected.

A trestle of greater length may of course be made with heavier timbers and by this construction a trestle may be erected the desired height and length to suit the size of a room for plastering or any other purpose but the trestle may be made of much lighter material to adapt it for the use of paper hangers and various other decorators and similar artisans not requiring an excessively heavy trestle. The legs are locked in their inclined position by pivoted bars 10 and 11 connected at their outer ends by rivets 12 or other suitable fastening devices to the legs or

standards and pivotally connected at their inner ends by a rivet 13. The bar 10 overlaps the bar 11 and is provided with a laterally projecting lug 14 which fits in a notch 15 of the bar 11 to limit the pivotal movement of the bars 10 and 11 in one direction so as to form a straight rigid brace for holding the legs laterally separated. Any other suitable means may of course be employed 5 for this purpose. The legs are equipped at their upper ends with integral inwardly projecting spurs 16 which are adapted to be embedded in the top timber or member 9 as clearly illustrated in Fig. 2 of the drawings 10 and the said timber is supported at the bottom by a longitudinal horizontally disposed rest 17 constructed of angle iron or other suitable material and having a side wing or flange and a supporting wing or flange 15 which is provided with integral spurs 18 adapted to be embedded in the lower edge or face of the timber or member 9. By this construction, the timber is securely held against longitudinal movement and is effectively prevented from slipping. The rest 20 is provided with a longitudinal slot 19 through which passes a pivot 20, consisting of a rivet or bolt headed at one end and suitably secured at the other end to the adjacent leg which also has rigidly secured to it a tapering horizontally disposed key 21 secured by rivets 22 or other suitable fastening devices to the leg and adapted to engage a groove or way formed by spaced 25 plates 23. The rivets 22, which are arranged close to the pivot, are sufficiently small so that they will not interfere with the turning of the rest on the pivot in swinging the rest from one position to the 30 other. The plates 23 are secured to the rest at the top and bottom of the slot 19 and their inner edges diverge slightly to enable the wedge to be tightly interlocked with the legs. The slot 19 extends beyond the upper 35 and lower pieces 23 and the groove or way formed by the same and the rest is adapted to be moved longitudinally to carry the groove or way out of engagement with the fixed wedge shaped key and enable the rest 40 to turn on the pivot 20 which is received in the extension of the slot 19. This will enable the rest to swing downwardly and fold 45 between the legs and permit the trestle to be compactly arranged for shipping, storing or 50 transporting.

Any other suitable means may of course be employed for slidably interlocking the rest with the legs. Also the L-shaped rest

may be rigidly fastened to the legs where a cheap construction of great strength is desired.

What is claimed is:—

1. A foldable trestle including oppositely inclined legs, an upper transverse connecting bar pivoted to the legs intermediate of the ends thereof to form upper clamping portions, a horizontally disposed timber supporting rest substantially L-shaped in construction secured to one of the legs and extending perpendicularly from the same in opposite directions and provided with timber engaging means, and means for connecting and locking the legs in their clamping position. 65

2. A foldable trestle of the class described including inclined legs or standards having upper clamping portions, and a rest pivotally mounted on one of the legs or standards, such leg or standard and rest being provided with coacting means for slidably 70 interlocking the rest with the leg or standard to support the rest in a horizontal position. 75

3. A foldable trestle including opposite inclined legs or standards having upper clamping portions, one of the legs or standards being provided with a pivot and having a horizontal key and a rest provided with a longitudinal slot receiving the said pivot and having a groove or way arranged 80 to coact with the key to interlock the rest with the legs or standards, said slot being extended beyond the said way to permit the rest to be swung on the pivot to fold the said rest between the legs or standards. 85

4. A foldable trestle including opposite inclined standards having upper clamping portions, one of the legs or standards being provided with a pivot and having a horizontally disposed tapered key located on the said pivot and a rest provided with a longitudinal slot to receive the pivot, said rest being also provided with spaced plates or members forming a groove or way and coacting with the key to lock the rest rigid in a horizontal position, said slot being extended beyond the plates or members to permit the rest to be turned on the pivot and folded between the standards. 90

In testimony whereof I affix my signature 105 in presence of two witnesses.

FRANK W. HELWIG.
